MEASURING-VALVE MECHANISM.

No. 809,439.

Specification of Letters Patent.

Patented Jan. 9, 1906.

Application filed January 28, 1905. Serial No. 243,159.

To all whom it may concern:

Be it known that I, RUDOLPH W. GOEB, a citizen of the United States, residing at St. Louis, Missouri, have invented a certain new and useful Improvement in Measuring-Valve Mechanisms, of which the following is a full, clear, and exact description, such as will enable others skilled in the art to which it appertains to make and use the same, reference 5 being had to the accompanying drawings, forming part of this specification, in which—

Figure 1 is a vertical sectional view through my improved measuring-valve mechanism. Fig. 2 is a sectional view on the line 2 2 of 15 Fig. 1. Fig. 3 is a top plan view; and Fig. 4 is a rear elevational view, partly in section.

This invention relates to a new and useful improvement in measuring-valve mechanisms, the object being to provide means for 20 adjusting the telescoping cylinders forming the measuring-chamber, whereby the cubical contents thereof may be regulated, and also to provide means whereby the valves which coöperate with the outer ends of the telescoping sections may be adjusted so as to be seated at the proper time with relation to each other.

With these objects in view the invention consists in the construction, arrangement, 30 and combination of the several parts, all as will be hereinafter described and afterward pointed out in the claims.

My improved measuring-valve mechanism is designed particularly for use in connection 35 with the machine for making pulp stoppers shown in an application filed by me on January 19, 1905, and serially numbered 241,865. The fluid to be measured is pulp-water—that is, water having about two grains of pulp per 40 cubic inch of water—although it is obvious that the present construction is applicable to other kinds of fluid.

In the drawings, 1 indicates the tank containing the fluid to be measured, and 2 indicates a trough arranged under the tank for 45 conducting off the fluid after it has been measured and issues from the measuring-chamber.

3 indicates a cylinder screwed into the bottom of the tank and having a seat at its upper edge, with which seat coöperates a valve 4, having, preferably, a rubber facing 4^a for coöperating with the valve-seat. Valve 4 is

provided with an interiorly-threaded stem 5, which is provided with a longitudinal rib 5^a 55 on its side, (see Fig. 2,) which rib coöperates with a spider 6, secured in the cylinder 3. By this construction the valve-stem is slideable longitudinally in the spider, but is prevented from rotation.

7 indicates a hollow cap arranged on the upper end of valve 4 for inclosing the upper threaded end of the operating-rod 8 and excluding the pulp-water therefrom. Rod 8 has threaded engagement with the valve 4. 65 The lower end of rod 8 passes through a sleeve 9, which sleeve carries a valve 10 at its upper end, said valve 10 having a facing of rubber 10^a coöperating with the seat on the lower end of a cylinder 11, said cylinder 70 11 having a sliding engagement with the cylinder 3, as will be hereinafter described. The lower end of sleeve 9 is provided with lateral flanges 9^a, forming a head. Sleeve 9 is also slotted longitudinally, as at 9^b, which slots 75 receive and coöperate with a cross-pin 12, carried by a rod 13. The lower end of rod 13 has a threaded engagement with a coupling-block 14, which is pivotally mounted upon an operating-lever 15. Lever 15 is vibrated, having a definite stroke; but it is obvious that instead of the motive power for actuating the rod 13 being in the form of a lever it could be in a different form.

Rod 8, which passes through the sleeve 9, 85 is made hollow at its lower end to receive the rod 13 and its cross-key 12, said cross-key passing through slots 8^a in the lower end of the rod 8. The lower end of rod 8 terminates in flanges 8^b, on which is seated a 90 spring 16, said spring bearing at its upper end against the flange 9^a. The energy of this spring is directed at all times to move the valves 4 and 10 toward each other—that is, rod 8 carries valve 4 and actuation of the 95 spring is to move these parts downwardly while sleeve 9 and its valve 10 are pressed upwardly.

In the position of the parts shown in Fig. 1 it will be seen that the cross-key 12 is located in the lower end of slot 9^b and in the upper end of slot 8^a. If lever 15 is moved upwardly, the cross-key will lift the rod 8 and valve 4 so as to admit the fluid in tank 1 into the chamber formed by the cylinders 3 100 and 11. In this movement the flange 8^a

compresses the spring 16 and more firmly seats the valve 10, the cross-key riding up in the slot 9^b and not disturbing the position of said valve 10. As lever 15 descends the 5 spring forces the valve 4 downwardly onto its seat until the cross-key reaches the position shown in Fig. 1, in which both valves are seated, the continued downward movement of lever 15 causing the cross-key 12 to 10 engage the sleeve 9 and move valve 10 away from its seat. This unseating of valve 10 enables the contents of the measuring-chamber to be discharged into the trough 2, and also the flange 9^a compresses the spring 16 and 15 causes the valve 4 to more firmly seat itself while the valve 10 is open. This operation of the valves in being alternately seated and unseated enables the fluid in tank 1 to fill the chamber at each elevation of valve 4, and the 20 contents in the chamber are then discharged when valve 10 is open, valve 4 being seated just previous to the opening of valve 10 and valve 10 likewise being seated just previous to the opening of valve 4.

25 In order to regulate the cubical contents of the measuring-chamber, the cylinders 3 and 11 have telescopic engagement with each other, the cylinder 3, as before described, being threaded into the lower end of 30 tank 1. Cylinder 11, as shown in Figs. 3 and 4, is supported by brackets 17, which brackets extend laterally through slots in the side walls of the trough 2. These brackets have threaded openings in their ends, through 35 which pass the threaded portions of rods 18. These rods are provided with knurled hand-wheels on their lower ends. Rods 18 pass through perforated lugs or ears 20, secured to the bottom of trough 2, in which said rods 40 are free to turn, collars being pinned on the rod to prevent longitudinal movement thereof, but permitting free rotation of the rod.

In order to adjust the cylinders with respect to each other, the rods 18 are rotated 45 and by reason of the threaded engagement with the bracket 17 will effect a vertical movement of cylinder 11, and thus increase or reduce the cubical capacity of the measuring-chamber. The adjustment of the cylinder 11 will of course change the relation of 50 the valves to the cylinders, and in order to reestablish the proper relation between the valves and their seats I first loosen a jam-nut 14^a, which locks the rod 13 in the coupling 14, 55 and then rotate the rod 8 and sleeve 9, which effects a changed relation between the valves. Thus if the cylinder 11 was moved up a short distance to reduce the cubical capacity of the measuring-chamber it will be obvious that 60 when the lever 15 is in its central position the valve 10 will be held off of its seat. By rotating the rod 13 in its coupling 14—say to the right—the cross-pin 12 will be elevated, permitting the sleeve 9 and its valve 10 to be 65 raised upwardly by the spring 16. The same

motion causes the rod 8 through its threaded engagement with the valve 4 to maintain the established relation between said valve 4 and the rod 13, the threads on rods 8 and 13 having the same pitch. The threaded connection between rod 8 and valve 4 is not for the purpose of adjusting the position of said valve, because the seat with which it coöperates is stationary, said threaded connection being used only for compensating purposes. 70

Should the cylinder 11 be moved downwardly to increase the cubical capacity of the measuring-chamber, it is obvious that the reverse of the operation above described will be necessary. The operator can determine 80 the seating positions of the valves by observing the position of the key 12 in the slots 8^a and 9^b.

I am aware that minor changes in the construction, arrangement, and combination of 85 the several parts of my device can be made and substituted for those herein shown and described without in the least departing from the nature and principle of my invention. 90

Having thus described the invention, what is claimed as new, and desired to be secured by Letters Patent, is—

1. In a measuring-valve mechanism, the combination with a measuring-chamber 95 comprising telescopic sections, a tank to which one of the sections is rigidly secured, the other section being slidable on the rigid section, of valves without an interposed spring between them and being adapted to 100 be moved longitudinally of said sections, one of said valves being adapted to be seated on the edge of the wall of the rigid section, and the other on the edge of the wall of the movable section, and a resiliently-controlled 105 means for the valves and common to both of them for alternately opening and closing said valves; substantially as described.

2. In a measuring-valve mechanism, the combination with a tank, of a measuring-chamber having two parts, one of which is slidable on the other, and one of said parts being rigid with the tank, of valves without an interposed spring between them, said valves controlling the inlet and exit openings 110 to and from said chamber, devices connected to said valves, and an expansible spring coöperating with said devices and whose energy is exerted to normally seat said valves; substantially as described. 115

3. In a measuring-valve mechanism, the combination with a casing including an extensible chamber comprising two parts, one of which is movable within the other, of operable valves in the ends of the casing for 125 controlling the inlet and discharge openings to and from said chamber and adapted to be moved longitudinally thereof, means for adjusting said valves to accommodate them to the movement of the movable part of the 130

chamber, said adjusting means also serving as operating means for said valves; substantially as described.

4. In a measuring-valve mechanism, the combination with a measuring-chamber, of valves for controlling the inlet and exit openings to and from said chamber, a rod on one of said valves having a flanged end, a sleeve on the other of said valves having a flanged end, said rod passing through said sleeve, and a spring interposed between the flanged ends of said rod and sleeve; substantially as described.

5. In a measuring-valve mechanism, the combination with a measuring-chamber, of a valve for closing the upper end of said chamber, a rod on said valve, a valve for closing the lower end of said chamber, a sleeve on said lower valve, through which sleeve said 20 rod passes, the lower end of said rod being hollow, said rod and said sleeve being slotted, a rod fitting in the hollow portion of the first-mentioned rod and having a cross-pin 25 engaging slots in said first-mentioned rod and sleeve, and a spring coöperating with said first-mentioned rod and said sleeve; substantially as described.

6. In a measuring-valve mechanism, the combination with a measuring-chamber, of 30 valves for controlling the inlet and outlet openings to and from said chamber, slotted members connected to said valves respectively, and a key passing through the slots of said members whereby when said key is 35 moved in one direction it raises one of said valves from its seat, and when said key is moved in the opposite direction it moves the other of said valves from its seat; substantially as described.

40 7. In a measuring-valve mechanism, the combination with a measuring-chamber, of valves for controlling the inlet and outlet openings to and from said chamber, slotted members connected to said valves respectively, a key passing through the slots of said members whereby when said key is moved in one direction it raises one of said valves from its seat, and when said key is moved in the opposite direction it moves the other of said 45 valves from its seat, and a spring for holding either of said valves to its seat while the other of said valves is unseated; substantially as described.

50 8. In a measuring-valve mechanism, the combination with the walls of a measuring-chamber, said walls being provided with valve-seats, one of said seats being fixed and the other movable, of means for adjusting the walls carrying the movable seat, 55 whereby the cubical capacity of the chamber

is changed, valves for coöperating with said seats, common means for operating said valves alternately, a compensating connection between one of said valves and said operating mechanism, and an adjusting mechanism between the other of said valves and said operating mechanism, whereby said last-mentioned valve may be adjusted to accommodate the changed position of its coöperating seat; substantially as described.

60 9. In a measuring-valve mechanism, the combination with telescoping walls forming a measuring-chamber, said walls having valve-seats at their ends, means for adjusting one wall with relation to the other where- 65 by the cubical capacity of said chamber is changed, valves coöperating with said seats, common means for alternately opening and closing said valves, means for accommodat- 70 ing the valves in the changed position of the telescoping walls, said last-mentioned means 75 operating independently of the valve-oper- 75 ating mechanism, whereby the same opening movement is imparted to both valves irre- 80 spective of the adjusted position of their co- 85 operating seats; substantially as described.

8. In a measuring-valve mechanism, the combination with a fixed cylinder having a valve-seat at its upper end, a valve coöper- 90 ating with said seat, means for holding said valve against rotation, a threaded rod engag- 95 ing said seat, a telescoping cylinder coöper- 100 ating with said first-mentioned cylinder, a valve which is seated against the lower end of said telescoping cylinder, means coöper- 105 ating with both of said valves to move them from their seats alternately, a spring for mov- 110 ing said valves to seating position and holding them seated, means for adjusting the position of the telescoping cylinder, means for 110 adjusting the position of the valve which co- 115 operates with said telescoping cylinder to accommodate said valve to the different positions of said cylinder, said adjusting mech- 115 anism being independent of the valve-oper- 120 ating mechanism and including the rod hav- 120 ing threaded engagement with the valve seated on the upper end of the fixed cylinder, which threaded engagement constitutes a compensating mechanism for permitting 125 said adjustment without disturbing the re- 125 lation of said valve to its fixed seat; sub- 130 stantially as described.

In testimony whereof I hereunto affix my signature, in the presence of two witnesses, this 23d day of January, 1905.

RUDOLPH W. GOEB.
